UNITED STATES PATENT OFFICE.

WILLIAM HOYT YOUNG, JR., OF PATERSON, NEW JERSEY.

SKATE OR OTHER RUNNER.

Application filed July 26, 1923. Serial No. 653,949.

To all whom it may concern:

Be it known that I, WILLIAM HOYT YOUNG, Jr., a citizen of the United States, residing at Paterson, in the county of Passaic and State of New Jersey, have invented 5 certain new and useful Improvements in Skates or Other Runners; and I do declare the following to be a full, clear, and exact description of the invention, such as will 10 enable others skilled in the art to which it appertains to make and use the same.

My invention relates to improvements in skates or other runners for use on ice or snow crust, the principal object being to 15 provide a simple and inexpensive construction, yet one which will be very desirable.

Another object is to provide a device of the class described consisting of a plate and a longitudinal runner strip of bamboo secured to the plate. 20

A still further object is to make unique provision for steering the device.

With the foregoing in view, the invention resides in the novel subject matter herein- 25 after described and claimed, the description being supplemented by the accompanying drawing.

Figure 1 is a side elevation of a skate constructed in accordance with my invention.

30 Figure 2 is a top plan view.

Figures 3 and 4 are sectional views on lines 3—3 and 4—4 of Fig. 2.

Figure 5 is a plan view of the metal plate before it is bent to shape.

35 The present disclosure of my invention is directed to the preferred form of construction where a skate is to be produced, and although I have restricted the description and illustration to a skate, it will be obvious that 40 certain features may be used in connection with other forms of runners.

In the drawing, the numeral 1 designates 45 an elongated sheet metal plate having the general contour of a shoe sole but of greater length, the heel portion of the plate being provided with integral ears 2 which are bent upwardly to engage the user's heel. Also, at suitable points, spurs 3 are stamped upwardly to engage the sole and heel of the 50 shoe and prevent slipping of the plate thereon. Upward stamping of these spurs, provides small openings 4 in the plate through which attaching fasteners may be driven if desired, or other preferred provision may be 55 made for securing the device to a shoe, and

in some instances, it need not be secured, if desired.

The front end of the plate 1 is curved upwardly as indicated at 5 and preferably has its front edge bent upon itself as indicated at 6 to prevent said edge from being injured and to generally stiffen the plate transversely. At the juncture of the upwardly curved end 5 with the horizontal portion of the plate 1, the latter is provided with a longitudinally elongated opening 7. A similar opening 8 is formed in an integral tongue 9 which inclines from the rear end of the plate 1. 60

Extending longitudinally along the lower 70 side of the plate 1 is a runner strip 10 formed of bamboo, the ends of said strip being passed upwardly through the openings 7 and 8 and secured upon the upper sides of the tongue 9 and the front end 5 of said plate, the strip being secured to these parts in any desired manner, for instance by passing loops of wire 11 through openings 12 and around the strip ends. Also, to insure 75 against any rearward sliding of the strip 10, I prefer to bend the rear terminal of the tongue 9 around the rear end of said strip as shown.

The opposite edges of the plate 1 are provided with forwardly diverging, longitudinally curved flanges 14 which are of less vertical height than the strip 10. Consequently, this strip takes the weight of the wearer when going straight ahead, but by 80 tilting the feet in one direction or the other, the flanges 14 of the two skates are brought against the supporting surface, and consequently the skates are caused to turn in one direction or the other. 90

By employing the construction shown and described or a substantial equivalent thereof, a device is provided which is extremely simple and inexpensive, yet will be very desirable and enjoyable when in use. As excellent results may be obtained from the 95 details disclosed, they may be followed if desired, but within the scope of the invention as claimed, numerous minor changes may be made.

100 I claim:

1. A skate comprising a plate having an opening adjacent at least one end and having said end turned upwardly, a runner strip 105 extending along the lower side of said plate and having one end turned upwardly 110

through said opening and disposed on top of said upwardly turned plate end, and means securing said strip to said plate.

2. A skate comprising a plate having its front end turned upwardly and having on its rear end an upwardly turned tongue, said plate being provided at the rear end of its horizontal portion with an opening, and a runner strip extending along said hori-

zontal portion and having its rear end 10 passed through said opening and disposed against the upper side of said tongue, the rear end of said tongue being bent around the rear end of said strip.

In testimony whereof I have hereunto 15 affixed my signature.

WILLIAM HOYT YOUNG, JR.
